UNITED STATES PATENT OFFICE.

HENRY A. WEIHMAN, OF PHILADELPHIA, PENNSYLVANIA, ASSIGNOR TO
SIMONS, BROTHER & CO., OF SAME PLACE.

DESIGN FOR A CANE OR UMBRELLA HANDLE.

SPECIFICATION forming part of Design No. 19,970, dated July 1, 1890.

Application filed April 15, 1890. Serial No. 348,080. Term of patent 3½ years.

To all whom it may concern:

Be it known that I, HENRY A. WEIHMAN, a citizen of the United States, residing in Philadelphia, in the county of Philadelphia and State of Pennsylvania, have invented and produced a new and original Design for Cane or Umbrella Handles, of which the following is a specification, reference being had to the accompanying drawing, forming part thereof.

10 In the drawing is shown a side elevation of a cane or umbrella handle illustrating my new design.

A is the body part, extending upwardly and terminating in the loop B, which gradually decreases in cross-section. The small end of the loop is finished with spiral ornamentation C upon its sides, said end meeting the body part A, as indicated in the drawing. The body part A is bounded on the bottom by a

band D of plain surface, and is encircled by 20 bands E, arranged spirally, substantially as shown, which bands are in the form of ribs of plain surface, and they are bounded upon each side by bold ornamentation G.

The handle is made of any suitable material.

Having now described my new design, what I claim as new, and desire to secure by Letters Patent, is—

The design for cane or umbrella handles, 30 substantially as herein described and shown.

In testimony of which invention I have hereunto set my hand.

HENRY A. WEIHMAN.
